UNITED STATES PATENT OFFICE.

HARRY H. GAGE, OF CHICAGO, ILLINOIS.

SOAP-FOUNTAIN.

1,157,860.

Specification of Letters Patent.

Patented Oct. 26, 1915.

Application filed November 28, 1913. Serial No. 803,104.

To all whom it may concern:

Be it known that I, HARRY H. GAGE, a citizen of the United States, residing at Chicago, in the county of Cook and State of Illinois, have invented a certain new and useful Improvement in Soap-Fountains, of which the following is a specification.

My invention relates to a liquid soap fountain and is illustrated in the accompanying 10 drawing, wherein—

Figure 1 is a side elevation with parts broken away and parts sectioned; and Fig. 2 is an enlarged detail cross section of the valve in the discharging position.

15 Like parts are indicated by the same letter in all the figures.

A is a liquid soap globe or apertured reservoir preferably of glass and associated with a holder A¹ attached at A² to a fixture 20 A³. It is provided with the relatively small inlet opening A⁴ covered by the screw cap A⁵. The globe is perforated opposite and below the inlet opening to receive the cylinder or valve housing B. This cylinder is 25 perforated at B¹ to permit the liquid soap about it within the globe to penetrate within the cylinder. It is also perforated at B² to permit a free circulation of the liquid soap through and therefore easy escape of the 30 same from the interior of the cylinder. The cylinder is provided with the ring C adapted to rest upon packing C¹ so as to prevent leakage around the cylinder through the opening in the bottom of the globe. The 35 cylinder is open at the bottom and provided with the perforations D.

The two-part piston or plunger valve consists of the stem E adapted to pass through a suitable aperture in the top of the cylinder. It is also provided with the disk E¹ 40 grooved at E² to receive the packing ring E³ whereby a close fit is made with the interior of the cylinder. The plunger E has a stem F of any desired shape around which is 45 formed a pocket G of any desired shape and size.

H is a plug on the lower part of the plunger E provided with a ledge J.

J¹ is a groove beneath the ledge adapted 50 to receive the packing J².

The lower end of the plunger E terminates in a hollow valve stem K having apertures K¹ at its upper end and K² near its lower end and the opening K³ at the lower end.

The cylinder is exteriorly screw-threaded 55 at L.

M is a valve bowl or apertured receptacle made of any desired material or any desired shape. It is apertured and screw-threaded above to receive the exterior screw-thread of 60 the cylinder and is associated with a packing M¹ placed between the upper part of such bowl and the lower part of the globe. The bowl is provided with a downwardly 65 projecting part or sleeve M² which is centrally perforated to permit the free passage of the cylindrical portion of the plunger. The inner walls of this downwardly projecting portion are adapted to be engaged by the packing J² to prevent leakage from 70 the bowl around the cylindrical portion of the plunger.

N is a spiral spring within the cylinder bearing against the top thereof and against the disk E¹ on the plunger and tending to 75 hold the plunger at its lower position, as indicated in Fig. 1.

O, O are openings in the upper part of the valve bowl to permit the free egress of air so that the liquid soap can flow into such 80 bowl rapidly.

It will be understood, of course, that the drawing is more or less diagrammatic and that many changes may be made without departing from the spirit of my invention. 85 The size, proportion and arrangement of the parts could be greatly altered and some could be dispensed with and others substituted for them without departing from the spirit of my invention.

90 The use and operation of my invention are as follows: Assuming that the parts are of the structure illustrated, they may be assembled as follows: The cap having been removed, the cylinder is dropped into position, and the opening beneath the cap need be no larger than would be sufficient to permit the cylinder to be thus introduced. The flange on the cylinder rests upon the packing so that when the parts are drawn together a tight connection is made. The cylinder in this position would project through the opening in the bottom of the globe. The valve bowl is now screwed into 95 position about the bottom of the cylinder, 100 the packing ring being inserted between the bowl and the globe, and when the bowl has been tightly screwed into position, the parts 105

will be in the position indicated in Fig. 1, and all leakage from the globe into the cylinder will be prevented by the packing E³ and between the globe and the cylinder and the bowl by the packing rings C¹ and M¹. There will be no soap in the bowl. If, now, the plunger be raised, against the action of the spring N by the hand applied to the lower end of the plunger cylinder, 10 into the position indicated in Fig. 2, the pockets in the plunger will be filled with soap which will readily flow in because the holes leading through the cylinder into such pockets may be of any number and size. 15 Indeed, the cylinder may be little more than a skeleton sufficient to serve as a guide for the plunger. When the hand pressure is released, gravity and the spring N will force the plunger downwardly in the position 20 shown in Fig. 1 and deposit a charge to the valve bowl. The parts are so proportioned that this charge will be much less than sufficient to fill the bowl, and it will flow freely into the bowl because the air will escape 25 from the openings O, O. The liquid will be prevented from flowing out of the bowl by the packing ring J² engaging the inner walls of the projection M² of the bowl. The device is now ready for use. When the user 30 applies pressure to the lower end of the plunger he will raise it until the openings K¹ are above the bottom of the bowl, whereupon the liquid soap will flow out through these openings into the cylinder at the lower 35 end of the plunger and out through the openings K² and K³ into the hand of the user. This same action, however, forces the pockets up into the globe in the position shown in Fig. 2 so that they can be refilled. 40 The proportions of the parts are such that the pockets are entirely disconnected from the interior of the globe before they are connected with the interior of the bowl, and therefore there is no intermediate position 45 at which the user can hold the parts so as to cause a steady flow of liquid soap therefrom. The use necessarily involves the withdrawal of a charge of liquid soap from the globe, then the separation of the charge 50 from the globe and from the bowl, then the discharge of the charge into the bowl, and by a subsequent reverse movement the discharge of said charge into the hand of the user.

55 I claim:

1. A liquid measuring and discharge device comprising an apertured reservoir, an apertured valve bowl in register therewith, a measuring valve housing located between 60 and partially within each of them, an aperture for communication with each of them, and having a rigid two-part valve mounted for reciprocation therein, the minimum distance between said apertures being greater 65 than the distance between the adjacent sides

of the valve parts, a discharge sleeve extending downwardly from the bowl, a hollow valve stem slidable therein and mounted upon the plunger and apertured adjacent thereto.

2. A liquid measuring and discharge device comprising an apertured reservoir, an apertured valve bowl in register therewith, a measuring valve housing located between and partially within, each of them, an aperture for communication with each of them, and having a rigid two-part valve mounted for reciprocation therein, the minimum distance between said apertures being greater than the distance between the adjacent sides 70 of the valve parts, a discharge sleeve extending downwardly from the bowl, a hollow valve stem slidable therein and mounted upon the plunger and apertured adjacent thereto, a valve seat surrounding the upper edge of said sleeve and yielding means for holding the end of the plunger seated upon 75 said valve seat.

3. A liquid measuring and discharge device comprising an apertured reservoir, an apertured valve bowl in register therewith, a measuring valve housing located between and partially within each of them, an aperture for communication with each of them, and having a rigid two-part valve mounted for reciprocation therein, the minimum distance between said apertures being greater than the distance between the adjacent sides 80 of the valve parts, a discharge sleeve extending downwardly from the bowl, a hollow valve stem slidable therein and mounted upon the plunger and apertured adjacent thereto, a valve seat surrounding the upper edge of said sleeve and yielding means for holding the end of the plunger seated upon 85 said valve seat.

4. A liquid measuring and discharge device comprising an apertured reservoir, an apertured valve bowl in register therewith, a measuring valve housing located between and partially within each of them, an aperture for communication with each of them, and having a rigid two-part valve mounted for reciprocation therein, the minimum distance between said apertures being greater than the distance between the adjacent sides 90 of the valve parts, a discharge sleeve extending downwardly from the bowl, a hollow valve stem slidable therein and mounted upon the plunger and apertured adjacent thereto, a valve seat surrounding the upper edge of said sleeve and yielding means for holding the end of the plunger seated upon 95 said valve seat.

5. A liquid measuring and discharge device comprising an apertured reservoir, an apertured valve bowl in register therewith, a measuring valve housing located between and partially within each of them, an aperture for communication with each of them, and having a rigid two-part valve mounted for reciprocation therein, the minimum distance between said apertures being greater than the distance between the adjacent sides 100 of the valve parts, a discharge sleeve extending downwardly from the bowl, a hollow valve stem slidable therein and mounted upon the plunger and apertured adjacent thereto, a valve seat surrounding the upper edge of said sleeve and yielding means for holding the end of the plunger seated upon 105 said valve seat, the bowl being apertured adjacent the reservoir to permit air circulation therein.

4. A soap fountain comprising a discharge apertured reservoir, an apertured valve bowl located beneath said discharge aperture, said bowl being open for ventilation, a combined measuring and valve plunger located between and partially within each of them, a valve housing partially in said reservoir and partially in said bowl, an apertured tubular valve mounted thereon to control the discharge from the valve bowl, said valve housing being apertured within the reservoir and within the bowl, the distance between said 110 apertures being such that they are never open to permit free passage from the reservoir to the bowl, the valve being necked down to provide an annular measuring compartment and yielding means for holding 115 said valves normally in the closed position.

5. A liquid measuring and discharge device, comprising a discharge apertured reservoir and apertured valve bowl in register therewith, a fixed valve housing located par- 120

tially in said reservoir and partially in said bowl and apertured within each, a two-part valve mounted for reciprocation within said housing, the two parts being connected by a 5 stem, the distance between the adjacent edges of the apertures being greater than the distance between the adjacent sides of said valve parts, a discharge sleeve downwardly extending from said receptacle and a hollow 10 valve stem slidably mounted therein carried by said valve, said valve stem being apertured adjacent its end and adjacent the valve, yielding means for holding said valve and stem normally down in closed position, 15 the relative positions of the apertures and valve parts being such that when in such closed positions the upper portion of the valve is below the upper apertures in the housing.

20 6. A liquid measuring and discharge device, comprising a discharge apertured reservoir and valve bowl in register therewith, a fixed valve housing located partially in said reservoir and partially in said bowl 25 and apertured within each, a two-part piston valve mounted for reciprocation within said sleeve, the two parts being connected by a stem, the distance between the adjacent edges of the apertures being greater than the 30 distance between the adjacent sides of said piston parts, a discharge sleeve downwardly extending from said receptacle and a hollow valve stem slidably mounted therein 35 carried by said piston valve, said valve stem being apertured adjacent its end and adja-

cent the piston valve, yielding means for holding said valve and stem normally, in closed position, the relative positions of the apertures and piston valve parts being such that when in such closed position the upper 40 portion of the valve is below the upper apertures in the housing, the lower portion of the valve is below the lower apertures in the housing, and the uppermost apertures in the valve stem are covered by the discharge 45 sleeve.

7. A soap fountain comprising a reservoir apertured at its bottom for a discharge, an apertured bowl located at and closing said discharge aperture, a valve housing projecting upwardly from said bowl through said aperture into said reservoir, the wall of said valve housing being ported, a two-part valve reciprocally mounted in said housing, a rod connecting said parts, said housing being 50 apertured both within the bowl and within the reservoir, a hollow valve stem mounted on said valve projecting outwardly through the bottom of said bowl, said stem being apertured adjacent its end and adjacent the 55 valve and yielding means for holding said valve in the down position resting on the bottom of the bowl.

In testimony whereof, I affix my signature in the presence of two witnesses this 21st 60 day of November, 1913.

HARRY H. GAGE.
